UNITED STATES PATENT OFFICE.

PETER G. VAN WIE, OF CLEVELAND, OHIO.

HOT-WATER GENERATOR.

SPECIFICATION forming part of Letters Patent No. 407,878, dated July 30, 1889.

Application filed November 7, 1888. Serial No. 290,202. (No model.)

To all whom it may concern:

Be it known that I, PETER G. VAN WIE, a citizen of the United States, and a resident of Cleveland, county of Cuyahoga, and State of Ohio, have invented certain new and useful Improvements in Hot-Water Generators, of which the following is a specification, the principle of the invention being herein explained and the best mode in which I have contemplated applying that principle, so as to distinguish it from other inventions.

My invention has for its objects, first, a hot-water generator provided with a non-radiating jacket inclosing the reservoir and conforming in shape thereto, whereby the heat arising from the burner is conserved and forced into close contact with the reservoir on its outward passage; second, a peculiar form of reservoir adapted to economically and rapidly heat the water; third, a peculiar formation of generator whereby the waste heat and gases on their outward passage are brought into contact with the supply-pipe, and thereby raise the temperature of the water entering the reservoir; fourth, valve mechanism intermediate of the generator and the boiler, whereby water may be drawn direct from the generator, if desired, the valve being so constructed as to afford free vent for the water at all times from the reservoir.

Referring to the drawings, Figure 1 is a central longitudinal vertical section of the generator. Fig. 2 is a transverse vertical section of the generator, taken at right angles to Fig. 1. Fig. 3 is a horizontal longitudinal section of the generator. Fig. 4 is a detail view of the mixing-chamber air-valve. Fig. 5 is a detail view of the two-way valve.

The generator is formed in two sections or portions, respectively, *a* *a'*, a cone-shaped reservoir *B* being vertically secured in any suitable manner in the central portion of section *a*, said reservoir being formed with an opening or deep depression *b* in its base of cone-frustum shape. An annular depending water-leg *b'* constitutes the lower portion of said reservoir and incloses or forms the wall of the opening *b*. The upper portion *b³* of said reservoir is formed as a continuous chamber in horizontal plane. Pipe *C'* leads from said reservoir to the usual form of boiler *C*. Located in said pipe and intermediate of the

reservoir and boiler is the two-way valve *c*, provided with the straight-way opening *c'* and transverse opening *c²*, formed at right angles to said first opening and extending therefrom to one periphery of the valve and adapted to register with the faucet *c³*. When the opening *c'* is in line and registers with the pipe *C'*, the water has free course to flow from the generator to the boiler; but when the valve is turned so as to register with the faucet connection with the boiler is severed and the water flows from the faucet. This is especially convenient, as in the morning, when starting a fire, the small quantity of water in the reservoir becomes heated much more quickly than the greater amount contained in the boiler, and this intermediate faucet renders it available.

By means of the engagement of shoulders *d* and *d'* the valve is prevented from being moved to any position where there is not free course or vent for the water passing from the reservoir—that is, the valve at all times permits the water to flow either into the boiler or out of the faucet and is and can be at no time confined within the generator, and hence all danger or possibility of explosion within the reservoir is prevented.

Within the generator is secured the sheet-metal cone or shaper *E*, that incloses the reservoir, and is used as a form or shaper, the space intermediate of said shaper and the wall of the generator being filled with the non-conducting and non-radiating packing or jacket *E'*, that may be made of mineral wool or other similar substance, whereby the heat is conserved, and, as the cone conforms in shape to the generator, the heat arising from the burner is compelled to pass close to the generator, and is thus utilized without waste. Said cone is provided at its upper portion with the vent *e*, that connects with the opening *e'* in the partition *e³* of the generator. At its lower portion the cone extends down about to a level with the top of the burner and is secured to the generator-wall. Flue *E²* is formed intermediate of said shaper and the reservoir, the lower part of said flue of shape substantially a counterpart to said reservoir, said flue having outlet through the vent *e*.

Two transverse heat-outlet openings *f* are

formed in the generator near the top of the water-leg and pass through the latter, affording means of escape for the hot air within the generator-base, preventing any packing 5 and deadening of said air and allowing free and rapid circulation. Said heat-outlet openings or cross-flues f connect the interior central opening b with said flue E^2 in a cross-sectional plane passing through the upper 10 portion of said water-leg b' .

Cold-water-supply pipe H enters section c' , is given three several turns vertically up and down in said section, and passes thence through section-wall e^3 and connects with the 15 bottom of the reservoir, opening into the same. As the heated air issues through opening e it passes down around the coils of pipe H and thence under partition J , up flue K , and out of vent e^2 , thus utilizing the waste 20 heat to raise the temperature of the water before entering the reservoir.

The foregoing description and accompanying drawings set forth in detail mechanism in embodiment of my invention. Change may 25 be made therein provided the principles of construction respectively recited in the following claims are employed. I therefore particularly point out and distinctly claim as my invention—

30 1. In a water-heater, the combination, with water-reservoir B , having its lower portion b' made in conical ring form and having its upper portion b^3 made as a continuous chamber in horizontal plane, of the flue E^2 , surrounding said reservoir, the lower portions of said flue E^2 being open and located substantially in the same horizontal plane with the bottom of said water-leg b' , said reservoir being provided with one or more cross-flues f , connecting 35 interior central opening b with said flue E^2 in a cross-sectional plane passing through the upper portion of said water-leg b' , substantially as set forth.

2. In a water-heater, the combination, with 40 water-reservoir B , having its lower portion formed as an annular conical water-leg b' and having its upper portion b^3 formed as a continuous chamber in cross-section, and central

vertical outlet-pipe b^2 , connecting with the central upper extremity of said central reservoir portion b^3 , of flue E^2 , surrounding said reservoir and connecting portion of said pipe b^2 , and said water-leg b' , having upper cross-sectional portion provided with one or more cross-cutting flues f , connecting the upper portion of the central conical depression b with said flue E^2 , substantially as set forth. 55

3. In a water-heater, the combination, with cone-shaped reservoir B and jacket E' , of non-radiating material, located intermediate 60 of the reservoir and the outer wall of the heater, of flue E^2 , formed intermediate of said jacket and the reservoir, said jacket inclosing said reservoir on the top and sides, substantially as set forth.

4. In a water-heater, the combination of cone-shaped reservoir B , provided with depending annular water-leg b' , vertical outlet-pipe b^2 , connecting with said reservoir, jacket E' , formed intermediate of the stove-wall and 70 the reservoir, said jacket inclosing said reservoir on the top and sides and surrounding said discharge-pipe b^2 , the interior shape of said jacket and the exterior shape of said reservoir where lying in the same horizontal plane 75 being substantially in counterpart of each other, and flue E^2 , being formed intermediate of the jacket and the reservoir, whereby the products of combustion are caused to pass close to the reservoir, and are kept in contact 80 with the same, substantially as set forth.

5. In a water-heater, the combination of cone-shaped reservoir B , shaper E , having its body portion of conical form and provided with the outlet-flue e , located above the top of 85 the reservoir, and mineral-wool jacket E' , intermediate of the shaper and the outer wall of the heater, said jacket inclosing said reservoir at top and sides, substantially as set forth.

In testimony that I claim the foregoing to 90 be my invention I have hereunto set my hand this 2d day of November, A. D. 1888.

PETER G. VAN WIE.
